CLAIM

The ornamental design for a set of phone chargers, as shown and described.

DESCRIPTION

FIG. 1 is a left front perspective view of a set of phone chargers;

FIG. 2 is a right front perspective view of a set of phone chargers;

FIG. 3 is a front elevation view thereof, the rear elevation view being a mirror image thereof;

FIG. 4 is a left elevation view thereof, the right elevation view being a mirror image thereof;

FIG. 5 is a top plan view thereof;

FIG. 6 is a bottom plan view thereof; and,

FIG. 7 is a left front perspective view of the set of phone chargers, shown in use.

The broken lines shown in the drawings depict portions of the set of phone chargers that form no part of the claimed design.

The cords are shown with symbolic breaks in their lengths. The appearance of any portion of the article between the break lines forms not part of the claimed design.
